UNITED STATES PATENT OFFICE.

HUGO BRUNINGHAUS, OF FREMONT, OHIO, ASSIGNOR TO THE HENKEL-CLAUSS COMPANY, OF FREMONT, OHIO, A CORPORATION OF OHIO.

COMPOSITE ARTICLE AND METHOD OF MAKING SAME.

Application filed June 7, 1928. Serial No. 283,476.

The invention relates articles made in part of celluloid or pyroxylin, and in part of some other substance of a different character such for example as metal, and the invention has to do more especially with the means for securing together the parts composed of the different materials.

In the making of various articles composed chiefly or essentially of metal, it has been sought to secure pleasing and ornamental effects by cementing to the surface of the metal, sheets, plates or blocks of celluloid or pyroxylin. These latter materials can be produced in excellent imitation of mother of pearl and in various colors so that very pleasing effects can be secured with them, but prior to my present improvements it has not been possible effectively and satisfactorily to secure the celluloid to the metal by cementing, and to secure the parts by rivets or the like is both more costly and not satisfactory as to appearance.

The chief objects of the invention are comprised in the provision of an improved construction and an improved method by the use of which composite articles made in part of celluloid and in part of metal, or substances other than metal reacting similarly to cements suitable for use with celluloid, can have their parts secured together effectively and satisfactorily by cement and at low cost.

Other objects more or less incidental or ancillary to the above will be apparent from the following description of some of the preferred embodiments of the invention and of the preferred procedure followed in producing said embodiments. In the description reference is had to the accompanying drawings.

In the drawings,
40 Fig. 1 is a side view of a nail file embodying my improvements;

Fig. 2 is a section on the line 2—2 of Fig. 1;

Fig. 3 is a side view of a nail file showing a modified form of construction;

45 Fig. 4 is a side view of a paper knife embodying the invention;

Fig. 5 is a section on the line 5—5 of Fig. 4;

Fig. 6 is a side view of a pair of shears embodying the invention;

Fig. 7 is a section on the line 7—7 of Fig. 6.

Referring first to Figs. 1 and 2, the nail file illustrated comprises the usual steel blade portion 1 with integral handle section 2. The 55 blade end of the handle portion has a hole 3

punched or otherwise formed therein and the other end of the handle portion 2 has a similarly formed hole 4. In the holes 3 and 4 are placed solid blocks 5 and 6, respectively, of celluloid, these blocks being preferably of approximately the same thickness as the portions of the steel handle adjacent thereto. On the opposite sides of the handle portion 2 are sheets or plates 7, 7 of celluloid or the like which may be made to simulate mother of pearl or may be given various colors if desired. The finishing plates 7, 7 are secured to the steel handle of the file by cementing them to the metal and to the celluloid blocks 5 and 6 with cement suitable for use with celluloid, a cement with a celluloid or lacquer base being preferred.

In attaching the celluloid plates to the metal handle the procedure is quite simple. The handle having been formed with the holes or openings 3 and 4 by punching, or otherwise, the blocks 5 and 6 of celluloid, which can advantageously be punched from scrap sheet material, are placed in the said openings. The blocks may be firmly secured in the openings, as by driving them in with forced fits and in many instances such securing of the blocks is to be preferred, particularly if an ornamental sheet or plate of celluloid is to be applied to but one side or surface of the piece of metal or the like. Where such ornamental sheets are to be applied to opposite surfaces of the metal such rigid securing of the celluloid inserts or blocks, though preferable, is not so essential. The inserts or blocks 3 and 6 having been placed in the openings and the surfaces of the metal handle having been cleaned, if need be, the celluloid cement is, in any suitable manner, applied to the spread over the inner surface of the celluloid sheets 7, 7 and the latter then applied to the sides of the metal handle 2 and firmly clamped thereon until the cement has had time to set. It will be understood, of course, that the cement may be applied both to the metal surface of the handle 2 and to the inner sides of the sheets 7, 7 before clamping the latter to the handle. The celluloid cement when applied to the surface of the celluloid sheets 7, 7 and of the celluloid blocks or inserts 5 and 6, somewhat softens the surfaces of the solid celluloid parts and then when the cement sets and hardens the celluloid parts 5, 6 and 7 are, so to speak, integrally welded together. The strong connection thus formed

between the inserts 5, 6 and the finishing plates 7, 7 supplements the cement connection between the plates 7, 7 and the metal handle 2 in such a manner that the finishing plates are effectively and permanently secured to the metal. In previous attempts to secure such celluloid finishing plates to articles of metal or the like it has been found impossible to satisfactorily secure the finishing plates to the metal by cementing, the finishing plates soon loosening and separating, especially where said plates are relatively thin and have a tendency to curl or cap up.

The use of solid blocks or inserts of celluloid not only has the advantage that such blocks can be rigidly and strongly secured in the body of metal or the like (as by using a forced fit as above described), but in addition they avoid the use of any considerable mass of liquid or soft cement in contact with the finishing plates with resultant correspondingly large shrinkage when the cement dries and sets. For example, I have attempted to secure the finishing plates 7, 7 to the metal handle by the use of soft cement in the openings 3 and 4, but the contraction of the relatively large mass of this cement is so marked and so strong that it draws the relatively thin celluloid sheets 7, 7 into the openings thus forming unsightly depressions in the finished handle as well as setting up severe strains in the finished celluloid structure which tend to weaken it and render it less able to resist mechanical shocks and stresses. It is to be understood that the solid block of celluloid can be introduced into the openings in the body of metal or the like by inserting plastic celluloid or thick celluloid cement in the opening and allowing it to harden therein before the finishing plates are cemented on the metal. However, I prefer to employ the method previously described since it lends itself to easy handling of the parts with resultant rapid production.

The nail file illustrated in Fig. 3 of the drawing is similar to that shown in Figs. 1 and 2 except that elongated rectangular openings 8 and 9 are formed in the metal handle of the file and correspondingly shaped solid celluloid blocks 10 and 11 are secured in the openings. Obviously the openings and inserts can be made of any form or shape best suited to the requirements of the particular form and construction of the article being produced. Aside from the form of the inserts the construction in Fig. 3 is similar to that of Figs. 1 and 2 and the procedure in making the handle is the same as above described.

In Figs. 4 and 5 of the drawing is illustrated a paper knife comprising a blade 12 with integral metal shank or handle 13 and finishing plates 14, 15 secured to the opposite flat surfaces of the handle. In this case the handle is formed with six openings 16, 16 in which are secured solid celluloid blocks or

inserts 17, 17 and the finishing plates 14, 15 are secured as in the case of the nail files by cementing them to the surfaces of the metal handle 13 and the celluloid inserts 17.

In Figs. 6 and 7 the invention is shown as applied to a pair of shears suitable for use with the paper knife as a desk set. In this instance each shear handle 18 is formed with a number of openings 19 in which are secured solid inserts 20 of celluloid, and finishing sheets or plates 21 of celluloid are cemented to the opposite flat surfaces of the handle 18 and to the celluloid inserts 20.

By the use of my improved method composite articles of celluloid and metal or the like having exceedingly pleasing appearance and great durability can be produced very easily and at low cost.

From the above described illustrations of the application of my improved method it will be apparent that it is applicable to a great variety of articles and it will also be obvious that the procedure followed in making the composite articles can be varied. It will therefore be understood that the invention is not limited to the articles illustrated nor to the particular procedure described, but that the scope of the invention is indicated by the appended claims.

What I claim is:

1. The process of securing a solid piece of celluloid to the surface of a body composed of material other than celluloid, said process comprising forming an opening in said body through its said surface; securing a solid piece of celluloid in said opening; and cementing the first named piece of celluloid to the surface of said body and to the surface of the piece of celluloid secured in its said opening. 100

2. The process of securing a relatively thin strip or sheet of celluloid to the surface of a body composed of material other than celluloid, which comprises forming an opening in said latter body through its said surface; securing a solid piece of celluloid in said opening with a surface thereof substantially flush with the surface of the said body adjacent the opening; and cementing the thin strip of celluloid to the said surfaces of the body and the piece of celluloid in the opening. 110

3. The process of securing solid bodies of celluloid to opposite surfaces of a solid body composed of material other than celluloid, which comprises forming an opening through the latter body; placing a piece of solid celluloid in the opening; and cementing the bodies of celluloid to the opposite surfaces of the other body and to the solid celluloid in the said opening. 120

4. The process of securing solid bodies of celluloid to opposite surfaces of a solid body composed of material other than celluloid, which comprises forming an opening through the latter body; placing a piece of solid cellu- 130

- loid in the opening with opposite surfaces of said piece of celluloid substantially flush with the said opposite surfaces of said body; and cementing the bodies of celluloid to the 5 opposite surfaces of the other body and of the piece of celluloid in the said opening.
5. The process of securing relatively thin strips or sheets of celluloid to opposite surfaces of a solid body composed of material 10 other than celluloid, which comprises forming on opening extending through the said body from one of the opposite surfaces to the other; inserting a piece of solid celluloid in the opening with opposite surfaces thereof 15 substantially flush with the said opposite surfaces of said body; and cementing the strips of celluloid to the opposite surfaces of the body and of the piece of celluloid in the opening.
- 20 6. A composite article comprising in combination a solid body of material other than celluloid formed with an opening therein; an insert of solid celluloid secured in said opening; and a piece of celluloid covering the 25 celluloid insert and the adjacent surface of the solid body and cemented to said surface and the insert.
7. A composite article comprising in combination a solid body of material other than 20 celluloid formed with an opening therein; an insert of solid celluloid secured in said opening with a surface thereof approximately flush with the adjacent surface of said body; and a piece of celluloid on the said surfaces 35 of the solid body and the insert and cemented thereto.
8. A composite article comprising in combination a solid body of material other than celluloid formed with an opening extending 40 through the body from one to another of two opposite surfaces thereof; an insert of solid celluloid in said opening; and pieces of celluloid cemented to the said opposite surfaces of the body and to the said celluloid insert.
- 45 9. A composite article comprising in combination a metal part formed with an opening therein; an insert of solid celluloid secured in said opening with a surface thereof approximately flush with a surface of the
- metal part; and a piece of celluloid on the 50 said surfaces of the celluloid insert and metal part and cemented thereto.
10. A composite article comprising in combination a metal part formed with an opening extending through the part from one to 55 another of two opposite surfaces thereof; an insert of solid celluloid in said opening; and pieces of celluloid cemented to the said opposite surfaces of the metal part and to said celluloid insert.
- 60 11. A nail file comprising in combination a metal file part proper; a metal handle part integral therewith and formed with an opening extending through it from one to the other of its opposite surfaces; an insert of solid celluloid in said opening; and pieces of celluloid cemented to the said opposite surfaces of the handle part and to the said celluloid insert.
- 65 12. A composite article comprising in combination a solid body of material other than celluloid formed with a plurality of openings therein; inserts of solid celluloid secured in said openings; and a piece of celluloid covering the celluloid inserts and the adjacent surface 70 of the solid body and cemented to said surface and the inserts.
- 75 13. A composite article comprising in combination a solid body of material other than celluloid formed with a plurality of openings 80 therein; inserts of solid celluloid secured in said openings with surfaces of the inserts approximately flush with the adjacent surface of said body; and a piece of celluloid on the said surfaces of the solid body and inserts 85 and cemented thereto.
- 90 14. A composite article comprising in combination a solid body of material other than celluloid formed with a plurality of openings extending through the body from one to another of two opposite surfaces thereof; inserts of solid celluloid in said openings; and pieces of celluloid cemented to the said opposite surfaces of the body and to the said celluloid inserts.
- 95 In testimony whereof, I hereunto affix my signature.

HUGO BRUNINGHAUS.
